UNITED STATES PATENT OFFICE.

CLARENCE U. BUCK, OF COUDERSPORT, PENNSYLVANIA, ASSIGNOR OF ONE-HALF TO
CHARLES H. BUCK, OF COUDERSPORT, PENNSYLVANIA.

PERCOLATOR.

959,110.

Specification of Letters Patent. Patented May 24, 1910.

Application filed April 21, 1909. Serial No. 491,371.

To all whom it may concern:

Be it known that I, CLARENCE U. BUCK, citizen of the United States, residing at Coudersport, in the county of Potter and State of Pennsylvania, have invented certain new and useful Improvements in Percolators, of which the following is a specification.

This invention comprehends certain new and useful improvements in percolators for use in preparing coffee, tea, or other infusions, and relates more particularly to devices of that type embodying a boiler designed to be partially filled with water and adapted when heated to generate steam, the pressure of the steam serving to forcibly eject the heated water from the boiler and through the charge holder to form the infusion.

The object of the invention is an improved percolator of this character which is simple, durable and efficient in construction and operation; which is susceptible of being conveniently cleaned to maintain the parts in a sanitary condition; and which is arranged to preclude excessive pressure in the boiler, so as to prevent explosions and admit of the device being used with safety.

With this and other objects in view that will more fully appear as the description proceeds, the invention consists in certain constructions and arrangements of the parts that I shall hereinafter fully describe, and then point out the novel features of in the appended claim.

For a full understanding of the invention and the merits thereof and also to acquire a knowledge of the details of construction, reference is to be had to the following description and accompanying drawing, in which:

Figure 1 is a vertical section of a percolator constructed in accordance with my invention; and Fig. 2 is an enlarged perspective view showing the screw cap, perforated disk and lower portion of the charge holder in juxtaposition.

Corresponding and like parts are referred to in the following description and indicated in all the views of the drawing by the same reference characters.

My improved percolator embodies a boiler 1 which in the present instance is in the form of a vertically disposed copper cylinder having upper and lower heads 2, the cyl-

inder heads being connected by a central 55 shaft 3 that serves to reinforce the structure as a whole. The heads 2 are substantially flat and the percolator is designed to rest upon the lower head, that serves as the bottom of the boiler, while the upper head is 60 adapted to constitute a support for a cup or other vessel for collecting the infusion. The boiler is formed in its side with an opening 4 by means of which water may be introduced therein, the opening being normally 65 closed by a screw plug 5. When heated the boiler is designed to generate steam, and as a precautionary measure to prevent the pressure within the boiler from becoming excessive, I provide a blow-off tube 10 that 70 passes through the upper head 2. This tube is formed at its upper end with a downwardly tapering valve seat that is controlled by an obconic relief valve 11, the stem 12 of the relief valve extending vertically 75 downwardly through the tube and being attached at its lower end to one end of a coil spring 13. The spring exerts linear tension on the stem whereby to insure of the valve being normally closed against its seat. 80

6 designates a vertically disposed pipe that is rigidly connected to the boiler and passes downwardly through the upper head 2 with its lower end submerged in the water and terminating in close proximity to the bottom thereof. The lower end of the pipe is open to afford egress for the water. Above the boiler the pipe 6 is equipped with a suitable handle 7 through the instrumentality of which the percolator may be conveniently carried from place to place. This pipe is bent horizontally at a predetermined distance above the boiler and is returned downwardly, as shown, the pipe being provided at its extremity with a relatively large 90 downwardly facing screw socket 8. A valve 9 is mounted in the pipe in proximity to the socket and is adapted to be manipulated by a suitable key, thus admitting of the valve being conveniently turned to close the pipe 100 for a purpose to be hereinafter disclosed.

A charge holder 14 has communication with the upper extremity of the pipe and is adapted to contain the ground coffee beans, tea leaves, or other charges with which the 105 water is to be impregnated. This charge holder is substantially in the form of a hollow cylinder which is open at its opposite

- ends and is provided in proximity to such ends with threaded portions 14^a. One of these threaded portions is adapted to be screwed into the socket 8, whereby to suspend the charge holder in superposed relation to the boiler. The lower end of the charge holder is closed by a screw cap 15 having a threaded annular rim which engages with the adjacent threaded portion 5 14^a the bottom of the cap being formed with a central aperture 16 to afford escape for the infusion. The bottom of the cap preferably tapers downwardly, so as to insure of all of the infusion flowing out of the 10 aperture 16. A perforated disk 17 is preferably held across the lower end of the charge holder by the screw cap and constitutes a strainer to prevent particles of the charge from escaping through the outlet 15 20 with the infusion.

Before describing the practical use of my improved percolator, it is to be assumed that the boiler is partially filled with water, that the holder contains the desired charge, 25 and that the valve 9 is closed. The device is then set upon the stove, or heat is otherwise suitably applied to the boiler, so as to heat the water and generate steam, the pressure of the steam tending to force the water 30 upwardly in the pipe 6, but this water cannot escape into the charge holder however, because of the closed valve 9. When the pressure of the steam has reached a certain degree, it is sufficient to unseat the relief 35 valve 11 against the force of the spring 13, some of the steam being thus permitted to escape through the blow-off tube 10 to prevent the pressure from becoming excessive and preclude a possible explosion. The escape of steam from the blow-off tube serves 40 to apprise the operator that the percolator is ready for use, whereupon a cup or other suitable vessel is placed on the upper head 2 below the charge holder, and the valve 9 45 opened. Water from the boiler is then forced through the pipe into the charge holder and through the particles of the charge packed in the latter, the infusion escaping through the aperture 16 into the 50 cup or vessel for receiving the same. It will be apparent that when sufficient infusion has been obtained the flow of the same may be arrested by closing the valve 9 to cut off the supply of water from the boiler. 55 It is to be observed that the upper head 2

is provided with an upstanding rim 18 to retain any drippings.

Among the many advantages residing in my improved structure, attention is particularly directed to the fact that the holder may 60 be readily detached from the socket to remove the old charge and introduce a new one, and that the parts of the charge holder may be separated from each other, so as to be susceptible of being thoroughly cleaned 65 to maintain the device in a sanitary condition.

Having thus described the invention what is claimed as new is:

A percolator of the character described, 70 comprising a vertically disposed boiler having a flat top and bottom, the top being designed to support a vessel for collecting the infusion, a vertically disposed water pipe passing through the top of the boiler and extending downwardly therein with its lower end open and arranged in close proximity to the bottom of the same, the pipe projecting upwardly beyond said top and having its upper end turned horizontally above 75 the boiler and terminating in a downwardly facing threaded socket, a container for a charge having its opposite ends open and threaded, one end of the container being screwed into the socket to suspend the container in vertically spaced relation to the boiler, a substantially flat strainer extending across the lower end of the container with the charge resting thereon, a screw cap disposed at such lower end and embodying 80 an annular rim having threaded engagement therewith and a bottom abutting the strainer to support the same in place, the bottom being substantially funnel-shaped and being provided with a central opening 85 arranged to discharge the infusion into a collecting vessel supported on the top of the boiler, a manually operable valve mounted in the water pipe for regulating the flow of water to the charge container, and a safety valve mounted in the upper portion of the boiler for relieving the same of excessive steam pressure when the aforementioned valve is closed.

In testimony whereof I affix my signature 105 in presence of two witnesses.

CLARENCE U. BUCK. [L. S.]
